US00D758966S

(12) **United States Design Patent**
Shigeno et al.

(10) **Patent No.:** US D758,966 S
(45) **Date of Patent:** ** Jun. 14, 2016

(54) **CASE WITH BATTERY CHARGER FOR ELECTRIC TOOTHBRUSH**

(71) Applicants: **Colgate-Palmolive Company**, New York, NY (US); **Omron Healthcare Co., Ltd.**, Kyoto (JP)

(72) Inventors: **Takashi Shigeno**, Tokyo (JP); **Kazuya Andachi**, Tokyo (JP); **Tamaki Ito**, Kyoto (JP)

(73) Assignees: **Colgate-Palmolive Company**, New York, NY (US); **Omron Healthcare Co., Ltd.** (JP)

(**) Term: **15 Years**

(21) Appl. No.: **29/533,387**

(22) Filed: **Jul. 16, 2015**

Related U.S. Application Data

(62) Division of application No. 29/456,355, filed on May 30, 2013, now Pat. No. Des. 736,701.
